UNITED STATES PATENT OFFICE

128,285

DESIGN FOR A FLUORESCENT LIGHTING FIXTURE

Max Herr, Chicago, Ill.

Application April 5, 1941, Serial No. 100,174

Term of patent 7 years

To all whom it may concern:

Be it known that I, Max Herr, a citizen of the United States, residing in the city of Chicago, county of Cook, and State of Illinois, have invented a new, original, and ornamental Design for Fluorescent Lighting Fixture, of which the following is a specification, reference being had to the accompanying drawing, forming part thereof.

Fig. I is a top plan view of a lighting fixture embodying my new design,

Fig. II is a front elevational view of the same.

Fig. III is an end view of the same.

I claim:

The ornamental design for a fluorescent lighting fixture, as shown.

MAX HERR.
